UNITED STATES PATENT OFFICE.

KARL KELLER, OF BROOKLYN, NEW YORK, ASSIGNOR TO J. E. WHITE MANUFACTURING COMPANY, OF BROOKLYN, NEW YORK, A CORPORATION OF NEW YORK.

LIGHTING FIXTURE.

1,423,331.

Specification of Letters Patent.

Patented July 18, 1922.

Application filed September 1, 1921. Serial No. 497,651.

To all whom it may concern:

Be it known that I, KARL KELLER, a citizen of the United States, residing at the borough of Brooklyn, in the county of 5 Kings, city and State of New York, have invented an Improvement in Lighting Fixtures, of which the following is a specification.

My invention relates to lighting fixtures, 10 particularly portable clusters, and the principal object of the invention is to provide means whereby the lamp sockets may be either raised or lowered to position the lamps with respect to shades which are of 15 various depths; also providing for the exclusion of dust from the shell, or the masking of the artistic or ornamental appearance of the fixture; another object being the provision of means whereby the lamp 20 sockets may be secured in such position to which they may be adjusted without danger of accidental displacement; another object is to provide a shell with a removable cap, containing no hickey, whereby ample space 25 is left within the shell to facilitate the wiring from the top of the cluster, also allowing for tapping the connections within the shell; also connecting the stem with the shell without threads thereby avoiding any liability of the stem snapping off at the shell 30 or unscrewing when shipped assembled.

The details of the construction are hereinafter particularly described.

In the accompanying drawing:

35 Figure 1, is an elevation of a lighting fixture embodying my invention, the stem being shown broken away and its lower end in section.

Fig. 2, is a sectional view showing the 40 interior of the shell with the lamp sockets and tubular stem partly broken away, and

Fig. 3, is a sectional view taken on the broken line 3—3 of Fig. 2.

Similar reference characters indicate like 45 parts throughout the several views.

Referring to the drawings, 10, indicates a shell formed of sheet brass, or other suitable material, and provided with a removable cap 11. This cap may be removably 50 secured to the shell in any suitable manner. I have shown headed lugs 12, on the rim of the shell, with bayonet slots 13 on the rim of the cover or cap for this purpose. The shell 10, is supported upon the upper end of the 55 tubular stem 14, the lower end of which may

be connected with any suitable base 15. The shell may be attached to the stem in any suitable manner, but to provide a firm connection, not liable to snap off or unscrew when shipped assembled, I prefer to reinforce the lower part of the shell by employing a ring or washer 16, seated in an annular depression in the bottom of the shell, the upper end of the stem 14, being reduced in diameter to pass through an opening in 60 the bottom of the shell and through the opening in the washer 16, leaving an annular shoulder 17, which abuts against the outer surface of the shell, the portion of the stem above the washer being upset over and upon 65 the top surface of the washer whereby the parts are firmly fastened together without possibility of accidental separation.

Two or more spaced vertical slots 18, are 70 formed in the shell 10, through which project the exteriorly threaded nipples 19, to which the lamp sockets 20, are screwed, the conductor wires (not shown), passing through these nipples and down within the tubular stem 14. The inner ends of the 75 nipples 19, are connected to shutter-flaps 21, in any suitable manner. I prefer to reduce the thickness of the metal at these ends and pass the same through openings in the flaps, the projecting ends then being upset over 80 the inner surface of the flaps, and they may be further secured by solder. These flaps 21, are of greater length and width than the slots 18 in the shell which they cover, and are curved to conform to the interior 85 curvature of the shell.

Each of these flaps 21, is provided with an integral lug 22, projecting on one side laterally therefrom and at approximately the longitudinal center of the flap. A threaded 90 hole is provided in the end of each lug 22. An oblong hole is also provided through the shell 10, at a predetermined distance to one side of each slot 18, and set screws 23, pass through these holes and through the threaded 95 holes in the lugs 22, thereby pivotally connecting the flaps 21, with the shell 10, but permitting movement of the set screws 23, lengthwise in the oblong holes in the shell, when the screws are slightly turned upon the 100 threaded holes in the flap lugs.

The set screws 23, not only act as pivot pins, but also assist in retaining the flaps in the desired position to which they may be 105 swung in order to raise or lower the nipples 110

19, within the slots 18, as such screws may be tightened to bind the lugs 22, tightly against the inner surface of the shell 10, but are not alone depended upon, because as will 5 be readily seen the lamp sockets 20, may be screwed upon the nipples 19, sufficiently to tightly press against the outer surface of the shell, thus there is a double pressure upon the shell one on its inner surface and 10 the other on its outer surface, whereby the nipples 19, may be firmly held in the desired position, thus positioning the lamps at the desired angle.

The flaps 21, cover the slots 18, at all 15 times, which prevents the entrance of dust into the shell 10, through such slots, and also avoids any disfigurement of the fixture, which might be occasioned if the openings in the shell were exposed.

20 While the lamp sockets may be securely held in the position to which they may be adjusted in the manner above described, without liability of accidental displacement, they can, when desired, be readily changed 25 to another angle by simply unscrewing the sockets and set screws sufficiently to remove the pressure of the sockets and flap lugs against the outer and inner surfaces of the shell, the oblong holes in the shell through 30 which the set screws 23 pass permitting such adjustment without undue friction or tendency to bind the flaps against the shell.

In the drawing I have indicated a shade 24, by dotted lines.

35 My invention provides a portable cluster adapted for use with shades of various depths, or in which the lamps may be positioned at different angles.

I claim as my invention:

40 1. A lighting fixture comprising a shell

provided with a plurality of spaced slots, shutters having a lug on one side with a threaded hole therein, set screws passing through holes in the shell and through said threaded holes in the lugs whereby said shutters are pivotally secured to the shell covering the slots therein at all times, and socket nipples carried by said shutters projecting through the slots in the shell. 45

2. A lighting fixture comprising a shell 50 provided with a plurality of spaced slots in its sides and lugs on its rim, a cap for the shell having bayonet slots in its rim to receive said lugs whereby the cap is removably secured to the shell, shutters having a 55 lug on one side with a threaded hole therein, set screws passing through holes in the shell and through said threaded holes in the lugs whereby said shutters are pivotally secured to the shell covering the slots therein at all 60 times, and socket nipples secured to the said shutters and projecting through the slots in the shell.

3. A lighting fixture comprising a shell 65 provided with a plurality of spaced vertical slots, a cap for the shell and means upon the shell and cap for removably securing the cap to the shell, flaps within the shell covering said slots, and each provided with a lateral lug having a threaded hole in its 70 end, set screws passing through holes in the shell and through said threaded holes in said lugs whereby said flaps are pivotally secured to the shell, socket nipples secured to said flaps, and projecting through said 75 slots, and a support for said shell.

Signed by me this 26th day of August, 1921.

KARL KELLER.
